UNITED STATES PATENT OFFICE.

ALEXANDER M. GOW, OF DULUTH, MINNESOTA.

CROSSOVER.

1,271,510.

Specification of Letters Patent.

Patented July 3, 1918.

Application filed November 26, 1917. Serial No. 304,600.

To all whom it may concern:

Be it known that I, ALEXANDER M. Gow, a citizen of the United States, and resident of Duluth, in the county of St. Louis and State of Minnesota, have invented certain new and useful Improvements in Crossovers, of which the following is a specification.

This invention relates to a crossover for railway tracks, and particularly to a temporary crossover.

One of the objects of this invention is to facilitate the transfer of an engine or a car from one track to another without the use of the usual frog or switch.

Another object is to provide a railway track crossover adapted to meet the various requirements for successful commercial use.

Generally speaking, these and other objects are accomplished by providing a crossover comprising a member which fits over the track rail and is provided with a crossover rail or guiding section.

The invention is illustrated on the accompanying sheets of drawings, in which—

Fig. 1 is a plan view of my crossover applied to a rail;

Fig. 2 is a side elevation of the same;

Fig. 3 is a diagrammatic view showing my crossover applied to a pair of tracks, showing connections whereby an engine or a car may be moved from one track to another and back to the first track;

Fig. 4 is an end view of the crossover;

Fig. 5 is a detail sectional view taken in the plane of line 5—5 of Fig. 1; and,

Fig. 6 is another detail sectional view taken in the plane of line 6—6 of Fig. 1.

The various novel features of my invention will be apparent from the following description and drawings and will be particularly pointed out in the appended claims.

The function of a crossover is to provide means whereby a car or locomotive may be transferred from one track to another without the use of the usual frog and switch. In contractor's service it is not infrequently desirable to transfer a steam shovel, for instance, from one track to another, under circumstances which make installing of a frog and switch very inconvenient. In railroad practice it not infrequently happens that a blockade or wreck will occur that prevents traffic on one line and a great deal of labor is involved in cutting in two frogs in the necessary switches to provide a "run-around" in order that the traffic may pass the block-

aded point on another track. Furthermore, the cutting in of a switch involves disturbing the existing track.

By referring to the figures of the drawing, it will be noted that my crossover is in the form of a single casting 10, a set of four being required to make a crossover, together with the necessary connecting rails 11. Eight of these crossovers are required to make a complete "run-around."

The main part of the crossover casting 10 is in the form of a channel having the top portion or web 12 connecting the two side portions 13 which diverge downwardly and are provided with laterally extending tie-engaging feet 14 having spike receiving notches 15, whereby the crossover may be secured in place. The sides 13 at the narrow end of the casting (see Fig. 3) are a relatively short distance apart and fit over the railroad rail 16 fairly closely, said sides 13 diverging toward the wide end of the casting (see Figs. 1, 4 and 6), whereby the crossover may be shifted laterally to accommodate the rail 16 on either side of the central supporting web 17 located within the channel portion of the crossover at the wide end thereof.

Formed integrally with the crossover casting 10 is a rail section 18 which at the narrow end of the casting has a very limited height, said section 18 increasing its height toward the wide end of the casting, whereby an engine or car may readily pass from the railroad track 16 onto the crossover rail section 18.

As shown in the figures of the drawing, the railroad rail 16 is received within one portion of the crossover, the upper part of the rail fitting between one of the side portions 13 of the casting and a shoulder 19 of a laterally extending reinforcing web 20 located under the central portion of the crossover rail section 18 at the wide end of the casting. With the crossover casting in the position shown, the crossover rail section 18 is at an angle with respect to the regular rail 16 for transferring an engine or car from one track to another in one direction. If it is desired to transfer the engine or car to a track in a different direction, the casting may be raised and shifted into a position to receive the railroad rail 16 in the right-hand half of the crossover casting, whereupon the railroad rail 16 will be held between the other side 13 of the casting and a

second shoulder 21 formed by the reinforcing web 20. The rail section 18 of the crossover casting does not extend the entire length of the casting, and preferably one end of the crossover rail section 18 is spaced from the wide end of the casting a sufficient amount to support the connecting rail section 11 in a grooved portion 22 formed in the upper central surface of the wide end of the crossover casting. The central reinforcing member 17 extends from the wide end of the casting toward the narrow end thereof a sufficient distance to give the required strength to the casting to prevent collapse along the central line thereof.

By means of this arrangement it is readily apparent that an engine or car may be transferred from one track to another and back again by setting the crossover castings in place and connecting said castings with the crossover rail sections, a minimum amount of time being required and at the same time obviating the necessity of using the usual frog and switch.

It is evident that there may be various modifications of the invention herein shown and described, and it is my intention to cover all such modifications which do not involve a departure from the spirit and scope of the invention as set forth in the following claims.

I claim:

1. A crossover comprising a body member provided with tie-engaging supporting flanges extending throughout the major length of the body and diverging from end to end thereof, and a wheel guiding element at the top of the body and extending longitudinally thereof substantially midway of the flanges.

2. A crossover consisting of a single casting having a top member, depending supporting flanges extending longitudinally of the body throughout substantially the major portion thereof and diverging from end to end thereof, said flanges constituting supports to engage cross-ties at opposite sides of a railroad rail, and a wheel guiding element at the upper surface of the top member and disposed longitudinally thereof substantially midway between the flanges.

3. A crossover comprising a body member provided with tie-engaging supporting flanges extending throughout the major length of the body and diverging from end to end thereof, and a wheel guiding element at the top of the body and extending longitudinally thereof substantially midway of the flanges, there being a rail receiving seat on the top of the crossover in longitudinal alinement with the wheel guiding element.

4. A crossover comprising a body member, tie-engaging supporting flanges depending from the body, diverging longitudinally thereof and extending throughout the major

length of the body, and a rail section extending longitudinally across the top of the body substantially midway between the flanges and having its upper surface inclined downwardly toward that end of the body to which the flanges converge.

5. A crossover comprising a body member, tie-engaging supporting flanges depending from the body, diverging longitudinally thereof and extending throughout the major length of the body, and a rail section extending longitudinally across the top of the body substantially midway between the flanges and having its upper surface inclined downwardly toward that end of the body to which the flanges converge, and a rail receiving seat provided upon the top of the body at the high end of the rail section.

6. A crossover comprising a tapered channel shaped member which fits over a railroad rail and on its upper surface is provided with a rail section which tapers from one height to another for gradually shifting the vertical position of the element being transferred from one track to another.

7. An integrally formed crossover comprising a tapered channel shaped member which fits over a railroad rail and is provided on its upper surface with a tapering rail section.

8. A crossover comprising a tapered channel shaped member adapted to be placed over a railroad rail and secured to the railroad ties, a tapered member secured to the upper side of the channel shaped member, and means whereby a railroad rail may be secured to the high end of said tapered member.

9. A crossover comprising a tapered channel shaped member adapted to be placed over a rail and secured to the ties, a tapered member secured to the upper side of the channel shaped member, and the upper surface of said channel member having means for maintaining a railroad rail in alinement with the high end of said tapered member.

10. A crossover comprising a tapered channel shaped member adapted to be placed over a railroad rail and secured to the ties, a tapered member secured to the top side of said channel member, said channel member being provided with a guide which maintains said channel member at an angle to said railroad rail when applied thereto, and means arranged on said channel member over said guide whereby a railroad rail may be secured to the high end of said tapered member.

11. In a crossover, in combination, a hooded member adapted to overlie a rail on either side thereof and rest on the ties, a tongue within said member to position same on the rail, an integral member on the top of said hood, overlying said tongue and tapered at one end to substantially the surface

of said rail, and means on said hood to direct and maintain another rail in alinement with said tapered member.

12. A crossover consisting of a single casting comprising a top, depending tie-engaging flanges extending throughout the major portion of the length of the casting and diverging from end to end, a rail section on the upper face of the top midway between the flanges, the upper surface of the rail section being inclined downwardly toward that end of the casting to which the flanges converge, the high end of the rail section

terminating short of the adjacent end of the casting, there being a rail receiving seat 15 in the upper face of the top at and in alinement with the high end of the rail section, and a supporting web depending from the top and disposed longitudinally beneath the rail section. 20

Signed at Duluth, Minnesota, this 27th day of November, A. D. 1917.
